Design for Border of seamless skirt,

Robert M. Bailey.

Pat. No. 2,087.

Patented June 13, 1865.

Robert M. Bailey
In presence of {
Samuel Wheeler
R. M. Bailey Jr.

R. M. Bailey, of Boston, Mass.

DES. 2087

Letters Patent No. 2087 Dated June 13-1865.

Design for a Third Border.

The schedule referred to in these Letters Patent and making part of the same.

To all whom it may concern:

Be it known that I, Robert Morris Bailey, of Boston, in the County of Suffolk, and State of Massachusetts, have originated and designed a new border for seamless skirts which I term the "Improved woven, trimmed, seamless Balmoral skirt border," of which the following is a full, clear and exact description, reference being had to the accompanying drawings, making a part of this specification.

The part represented in the drawing between A and B consists of a series of black and white stripes of about equal breadth. From B to C the stripes gradually increase in breadth; from C to D, there is one broad, black stripe; from D to E, the stripes gradually increase in breadth, and from E to F, the alternate black and white stripes are again of about equal breadth.

The arrow shows the direction that the border runs, at or near the bottom of the skirt or Balmoral—the stripes being continuous around the whole garment.

What I claim as my invention and desire to secure by Letters Patent is the design or pattern for borders of seamless skirts, as aforesaid.

To all whom it may concern:

Be it known that I, Elias Brown, of Wappingers Falls, Dutchess County, New York, have invented a new and ornamental Design for Combs, and I do hereby declare that the following is a full, clear and exact description thereof, which will enable those skilled in the art to make and use the same, reference being had to the accompanying drawings forming part of this specification.

The drawing is a side elevation of my improvement.

This improvement is intended for the ornamentation of the upper parts of hair combs.

My improvement is especially applicable to that species of ornamentation in which a series of balls or spherical shaped knobs or projections are attached to the comb.

My improved design consists in having the centre of each of the balls or spherical shaped projections provided with a central point or eye, of metal or other suitable material, which shall in composition or color present an ornamental contrast to the material composing the balls or projections.

As in the comb B the balls and at the metallic points or eyes.

These ornamental metallic eyes or points are composed of pins of metal and pass through the balls, their inner ends being clinched upon the inside of the comb in such a manner that the heads of the pins will occupy a central position upon the exterior of the balls or projections, forming ornamental points or eyes thereon and thus greatly adding to the ornamentation of the comb.

On carrying out my invention any desired number of balls having eyes or joints may be applied to any species of comb.

Having thus described my invention I claim as new and desire to secure by Letters Patent.

The within described design or ornament for skirts or balmorals, as herewith set forth.
